STRIP PUNCHING MACHINE

Harvey B. Lindsay, Evanston, Ill., assignor to
Dry-Zero Corporation, Chicago, Ill., a corpora-
tion of Delaware

Application June 4, 1941, Serial No. 396,533

10 Claims. (Cl. 164—90)

This invention relates to improvements in multiple punch presses and similar machines for forming holes, cuts, indentations, or similar effects in metal strips, bars, plates or the like, in which machines a plurality of individual punch cages or like tool-supporting structures are mounted for adjustment along the frame of the machine so as to produce a plurality of such holes or effects simultaneously at predetermined, exactly spaced intervals.

The principal object of this invention is greatly to speed set-ups, or changes of arrangement or spacing of such cages along the machine, by eliminating the necessity heretofore of removing from the machine each of such of said cages as in the next set-up are not required to be operative, and subsequently putting cages back in the machine when for the following set-up an increased number thereof are required to be operative.

I find that set-up time can be reduced as much as 75% by allowing the maximum number of cages to remain in the press rail or bed, and selectively spacing (when necessary) and operating only those desired to be operative by means of the key bar hereinafter described. This also reduces opportunity for errors in set-up practically to nil.

A further object of the invention is to provide an improved means for assisting in the adjustment of the individual punch cages at predetermined, properly spaced intervals whenever the cages are to be reset, said means including a master or key bar which also serves as the means for selectively operating, as stated above, only such cages as may be required for the particular cage settings called for by said master or key bar.

A further object of the invention is to provide a novel combination of cages, some of which have single or individual tools which are independently adjustable toward and away from each other, while other cages have a plurality of spaced tools so designed that they will always form a direct pattern of holes or similar effects at any desired and predetermined location on the bar.

A still further object of the invention is to provide an improved and simple form of cage especially adapted for feeding metal strips or the like lengthwise along the frame of the machine so that a plurality of separate units or lengths of metal strip, as determined by the particular master or key bar being used, may be

punched or otherwise operated upon simultaneously.

As heretofore constructed, multiple punch presses of the character above mentioned have usually included an elongated base frame on which is mounted a plurality of individual punch cages, each carrying both male and female parts of the punch and all arranged for simultaneous operation by a single elongated presser bar. The cages have been slidable along the base frame with means for adjusting their lateral spacings by a certain standard unitary length, as for instance by one-half inch or multiple thereof.

United States Patent No. 2,209,407 illustrates a machine of this character including a plurality of tool cages and means for adjusting and locking them simultaneously at predetermined spaced intervals. It will be observed, however, that with machines of this general character considerable manipulation is required to reset the cages, that the operator must make careful measurements as to their preliminary or rough adjustments, and must remove or insert separate individual cages along the frame so as to have the exact number of cages required for each job.

In carrying out my invention I provide an improved construction and arrangement including a plurality of cages (preferably equal to the maximum number of cages likely to be needed in any punching schedule) that are individually adjustable along the frame, together with a plurality of individual master or key bars, each made up in advance in accordance with a specific strip length and hole spacing required. Each master or key bar is provided with a plurality of lugs projecting from one face thereof, which lugs are exactly spaced at the predetermined intervals to be punched in the strip material or the like. Whenever it is desired to reset the cages in accordance with any one of these master bars, the latter is placed along the frame and is used to indicate a rough spacing adjustment of the cages, wherein one cage will be moved to position opposite each one of the lugs on the master bar, the intermediate cages not having to be removed as they will not be operative. Thereafter the master bar is placed along the top of the cages so that the lugs selectively engage only the plungers of those cages that are to be used. The cages are finally locked in their exact spaced relationship by suitable means.

As a further feature of my invention, it will be observed that the master or key bar may have an end-position means especially adapted to co-

operate with a special form of cage having two or more punches arranged at fixed spaced relationship. These multiple cages are especially adapted to produce a pair of holes spaced apart a standard distance, at adjacent ends of the final metal strip, as desired in many instances, whereas as the individual or single punch cages between the multiple punch cages are especially adapted to form intermediate, individual holes which are preferably spaced at relatively greater intervals than the standard end-holes.

The invention may best be understood by reference to the accompanying drawing, in which:

Fig. 1 is a fragmentary front view of a multiple press constructed in accordance with my invention.

Fig. 2 is an enlarged bottom view of a master or key bar of the kind suitable for use with the multiple press shown in Fig. 1.

Fig. 3 is an enlarged cross-section of the machine shown in Fig. 1, showing the cage in locked position on the base rail and with the master bar in cooperating engagement with the punch member carried by said cage.

Fig. 4 is an enlarged perspective view showing one end of the master bar illustrated in Fig. 2.

Referring now to details of the embodiment of my invention illustrated in the drawing: 10 indicates generally the frame of a punch press having an elongated cooperating ram 9, and a U-shaped rail member 11 with upstanding rear and front channel members 12 and 13 between which is slidably mounted a plurality of individual cages 14 and a plurality of multiple cages 14^a, 14^a. Each individual cage includes a base 15 on which is mounted a female die member 16 normally spaced below a male punch member or plunger 17. The male punch member or plunger 17 is slidable in a vertically disposed guide 18 mounted on a cross member 19 supported at opposite ends by front and rear plates 20 and 21 connected to the base member 15, so as to form an open frame for receiving the strip of metal to be operated upon, herein indicated at 22. The plunger 17 extends above the guide 18 and has an enlarged head 23 with a coil spring 24 interposed between said head and said guide so that normally said plunger is withdrawn upwardly from the die 16, as shown in Fig. 3.

Each of the cages is adapted to be individually locked against lateral displacement along the base rail 11 by means of one or more removable locking pins 25 each having a tapered end 26 adapted to fit in an opposed pair of holes 27 formed in the front and rear channel members 12 and 13 of said base rail, and also extending through the upright side walls 20 and 21 of the cage. A plurality of such holes 27, 27 are formed at equi-spaced intervals along the entire length of the base rail (for instance at intervals at $\frac{1}{2}$ inch) as indicated in Fig. 1, so that said cages may be accurately adjusted at various multiples of such intervals, as will hereinafter appear.

The multiple cages 14^a, 14^a may be substantially the same as the individual cages 14, excepting that they are substantially longer in the direction of the base rail so as to accommodate at least one pair of dies mounted thereon. Each pair of dies on said multiple cages 14^a are preferably arranged at a relatively small interval so as to form two holes at a standard spacing, for use at the opposite ends of each severed metal strip, as will hereinafter more fully appear. The multiple cages at the extreme ends of the machine, however, only require a single pair of dies, to form

the two end holes in the outer end of the metal strip at the end of the rail.

The key bar 30 shown in detail in Figs. 2 and 4 illustrates one of a large number of such key bars that may be made up in advance to determine various lengths and spacings of the holes to be formed in different metal strips. The key bar here shown for illustrative purposes consists of an elongated flat strip of metal 31 having a plurality of lugs or bosses 32, 32 fixed along one face thereof at the exact spacing intervals desired for the particular length and punching arrangement of strip to be punched. Each lug or boss 32 has a cylindrical recess 33 at its end adapted to fit over and receive a head 23 of a plunger 17 in close fitting engagement. A locating hole 34 is formed through the bar near opposite ends thereof. These holes are adapted to cooperate with locating pins 35, 35 provided on the multiple cages 14^a, 14^a, as will presently appear. In the form of key bar shown herein, the two lugs 32, 32 nearest the ends of the bar are located at a standardized distance fairly close together, as for instance 2 inches between centers, as is desirable in many instances where the end holes in the strip are to be used for connecting frame members thereto. The intermediate lugs are spaced at a greater interval from each other, but always at a multiple of the distance between adjacent locking holes 27, 27 formed along the base rail (for instance, on multiples of one-half inch). It will be observed that the standardized distance between each pair of dies of the multiple cages 14^a as well as the corresponding distance between the two end lugs 32, 32 at opposite ends of the key bar need not necessarily be spaced apart on multiples of one-half inch, since each of the multiple cages are adjustable and locked as a unit along the base rail. It will be understood, of course, that the length of the key bars will vary as will also the spacing and number of the intermediate lugs 32 thereon, depending upon the particular cage settings desired.

The use and operation of the apparatus hereinabove described will now be understood as follows:

The punch press is initially set up with a large number of cages of both the single and multiple type mounted along the base rail 11, the number of cages usually being sufficient to produce approximately the maximum number of holes that the machine may be called upon to produce.

Assuming that the work, comprising the continuous metal strip 22, is to be punched to form a plurality of separate metal strips similar to that determined by the key bar 30 shown in Fig. 2, one of said key bars is placed along the front of the cages with its end positioning hole 34 registering with the positioning pin 35 on the multiple cage 14^a at the extreme end of the machine. An adjacent multiple cage 14^a is then slid along the base rail so that its positioning pin 35 is in registry with the end-positioning hole at the opposite end of the key bar. The positioning pins on the two multiple cages may then be engaged in the end holes of the key bar, preferably with the latter bar inverted so that the lugs are facing upwardly as indicated in dotted lines in Fig. 3. Certain of the single cages are then slid along the base rail so as to be given a rough preliminary adjustment, with one plunger head opposite each one of the intermediate lugs 32 of the key bar. As the several plungers are thus brought into rough alignment with the lugs on the key bar, their respective cages can be locked accu-

rately in place by their pins 25. Said pins being tapered as shown, act to give a final adjustment of the cages at the exact spaced intervals desired.

The key bar is then removed from the positioning pins 35 on the front of the cages and is transferred in inverted position to the top of the plungers 17 so that the plunger heads 23 of those cages that have been previously locked into desired spaced relationship as above described, will be engaged within the recesses 33 of the respective lugs 32 of the key bar. When, as usual, several separate strips are to be made simultaneously in accordance with other key bars, the rough adjustment, and final locking of other cages along the rail is repeated as before, utilizing other key bars (of either the same or of different pattern as desired) until a plurality of key bars are mounted in end to end relation along the tops of those plungers that may be required, and usually extending successively for substantially the full length of the base rail.

The machine is so arranged that when the ram 9 is lowered its movement is limited so that it depresses all the key bars uniformly, moving the latter only a short distance which is sufficient to operate selectively the plungers with which the lugs on said bars are engaged, without operating the remaining plungers on the intermediate cages along the base rail, as indicated in dotted lines in Fig. 3. Thus a large number of cages may remain along the rail at all times and without requiring removal or replacement when they are reset for different spacings.

It will be understood that the intermediate multiple cages 14 are primarily intended to be disposed at the point where work-strip 22 is to be provided with additional holes for subsequently fastening other members thereto, or where the continuous work-strip 22 is to be cut or severed along the line midway the ends of said multiple cages so as to form two separate strips. However, these multiple cages 14^a are not necessarily used at such severing position between adjacent ends of a final strip. In some instances, the multiple cages 14^a may be employed in the same manner as in individual cages, by utilizing only one of their plungers. In other instances two or more plungers of a multiple cage can be employed intermediate the ends of a strip to form holes for an intermediate spreader or cross member, when desired.

Referring now more particularly to the preferred form of cage disclosed herein, it will be observed that the open frame arrangement with side walls 20 and 21 not only provides a substantial punch support permitting a continuous work-strip to be passed lengthwise through the machine as previously described, but that various inserts, such as blocks 43, 40 may be inserted between the side walls as required to position and guide work-strips of various widths and shapes during the punching operation, and to hold said strips down while the punch is being removed or stripped from the work.

In Fig. 3 a modified form of work-strip is indicated at 22^a shown in dotted lines with its lateral margins in guiding engagement beneath the blocks 43, 40. Obviously the shape and size of these blocks will be varied to accommodate different shapes as required.

Although I have shown and described one particular embodiment of my invention, it will be understood that I do not wish to be limited to the exact construction shown and described, but

that various changes and modifications may be made without departing from the spirit and scope of my invention as defined in the appended claims.

5. I claim as my invention:

1. In a multiple tool machine, a base rail, a plurality of tool cages adjustable along said base rail, and a key bar having a plurality of lugs therealong at predetermined spaced intervals, said lugs including positive guiding means detachably engageable with said tool cages and providing a fixed spacing means therefor at correspondingly predetermined intervals, and means for moving said key bar so as to operate said tool cages simultaneously.

2. In a multiple tool machine, a base rail, a plurality of tool cages, means including a tapered adjusting device for locking said tool cages along said base rail in independently selective spaced relation to each other at predetermined equal intervals, and a key bar having a plurality of lugs fixed therealong at predetermined spaced intervals disposed at certain multiples of the aforesaid predetermined equal intervals, the lugs on said key bar being adapted to indicate a preliminary rough adjustment of said tool cages along said base rail, and said lugs being detachably engageable with their respective tool cages so that the latter will be operated simultaneously by the movement of said key bar.

3. In combination with a multiple punch press having a base rail, a plurality of punch cages slidably adjustable in independently selective spaced relation therealong, and a presser bar movable toward and away from said punch cages, means including a tapered locking device for adjusting said cages along said base rail on centers of predetermined equal intervals, and a key bar having operating members fixed therealong at predetermined spaced intervals, said key bar being adapted to be interposed between said presser bar and said punch cages with its operating members detachably engaged with said punch cages for selective operation thereof.

4. In combination with a multiple punch press having a base rail, a plurality of punch cages slidably adjustable in independently selective spaced relation therealong, a presser bar movable toward and away from said punch cages, means including a tapered locking device for adjusting said cages along said base rail on centers of predetermined equal intervals, and a key bar having operating members fixed therealong at predetermined spaced intervals, said key bar being adapted to be interposed between said presser bar and said punch cages with its operating members detachably engaged with said cages for selective operation thereof, and the operating members on said key bar also being adapted to indicate a preliminary rough adjusting means for said punch cages before said cages are locked in position to be operatively engaged by said key bar.

5. In combination with a multiple punch press having a base rail, a plurality of punch cages slidably adjustable in independently spaced relation thereon, and a presser bar disposed along said base rail, certain of said punch cages having a single punch member carried thereby and certain other of said punch cages having a pair of punch members disposed at relatively short predetermined equal intervals, means for locking said punch cages along said rail in independently selective spaced relation to each other on centers of predetermined equal intervals, and a key bar adapted to indicate spacings of said cages at vary-

ing predetermined intervals forming multiples of the predetermined equal intervals aforesaid, said key bar having a plurality of operating members thereon spaced at such varying predetermined intervals and including a pair of operating members at opposite ends thereof disposed at intervals corresponding with the pair of plunger members carried by said multiple punch cages, said key bar being adapted to have its operating members detachably engaged with correspondingly spaced plungers of said multiple and individual punch cages, and said key bar being arranged to be directly engaged by said presser bar so as to operate selectively the respective plungers engaged by the operating members on said key bar.

6. In combination with a multiple punch press having a base rail, a plurality of punch cages slidably adjustable in independently spaced relation thereon, and a presser bar disposed along said base rail over said punch cages, certain of said punch cages having a single punch member carried thereby and certain other of said punch cages having a pair of punch members disposed at relatively short predetermined equal intervals, means for adjusting said tool cages along said rail in independently selective spaced relation to each other on centers of predetermined equal intervals, and a key bar adapted to assist in spacing said cages at varying predetermined intervals forming multiples of the predetermined equal intervals aforesaid, said key bar having a plurality of operating members thereon spaced at such varying predetermined intervals and including a pair of operating members at opposite ends thereof disposed at intervals corresponding with the pair of plunger members carried by said multiple punch cages, said key bar being adapted to have its operating members detachably engaged with correspondingly spaced plungers of said multiple and individual punch cages and with said key bar being arranged to be directly operated by said presser bar so as to operate the respective plungers engaged by said key bar selectively and independently of other punch cages that may remain on said base rail.

7. In a multiple punching machine, a base rail, a ram, a plurality of punch cages slidably adjustable along said base rail in independently selective spaced relation to each other, certain of said punch cages having a single punch member carried thereby and certain other of said cages having a pair of punch members disposed at relatively short predetermined equal intervals thereon, a key bar having a plurality of operating members fixed thereon at varying predetermined intervals,

including a pair of operating members at each end thereof disposed at intervals corresponding with the pair of punch members carried by said multiple punch cages, and other operating members intermediate its ends disposed at relatively wider intervals, temporary positioning means adjacent opposite ends of said key bar adapted for detachable connection with said multiple punch cages to provide a preliminary adjustment of two of said multiple punch cages relative to each other and permitting a preliminary sliding adjustment of intermediate single punch cages into alignment with the intermediate operating members on said key bar, the operating members on said key bar being detachably engageable with the correspondingly spaced punch members by movement of said key bar into position between said ram and said punch members so as to operate selectively the punch members engaged by the operating members on said key bar.

8. In a multiple tool machine, a base rail, a plurality of tool-carrying cages adjustable along said rail, a key bar having lugs fixed thereon and detachably engageable with the tools of certain of said cages, to provide fixed spacing means for the latter, and a ram with sufficient stroke to operate selectively such tools so engaged, but insufficient to operate any tools not so engaged.

9. In a multiple tool machine, a base rail, a plurality of tool-carrying cages adjustable along said rail, some of said cages having a single tool and certain other of said cages having a plurality of tools disposed at predetermined spaced intervals thereon, a key bar having lugs fixed thereon and detachably engageable with the tools of certain of said single and plural tool cages, and a ram with sufficient stroke to operate selectively such tools so engaged but insufficient to operate any tools not so engaged.

10. In a multiple tool machine, a base rail, a plurality of tool-carrying cages adjustable along said rail, some of said cages having a single tool and certain other of said cages having a plurality of tools disposed at predetermined spaced intervals thereon, a key bar having lugs fixed thereon at predetermined intervals, said lugs being adapted to indicate a preliminary rough setting for employing certain of said single and plural tool cages, and thereafter being detachably engageable with the tools of said certain single and plural tool cages, and a ram with sufficient stroke to operate selectively such tools so engaged by said lugs, but insufficient to operate any tools not so engaged.

HARVEY B. LINDSAY.
